UNITED STATES PATENT OFFICE

EUGEN HABER, OF BERLIN-CHARLOTTENBURG, GERMANY

IRON-PLATE CHIMNEY

Application filed December 27, 1927, Serial No. 242,849, and in Germany January 5, 1927.

This invention relates to an improved construction of high, isolated iron-plate chimneys, constructed so that a platform, adapted to be hoisted and lowered, can be securely fixed on the chimney to be used, on the one hand, at the building of the chimney and, on the other hand, at any time without auxiliary scaffolding for re-painting the chimney.

The several sections of the chimney consist each of a certain number of elements of the height of the section which, when united, form a cylinder and which are connected the one with the others by longitudinal irons fixed by rivets and designed to serve as guides for the rollers of the platform.

A further characteristic feature of the invention is that the upper edge of the iron-plate-chimney is protected against the action of the rain water by a protecting ring so that premature destruction by rusting is prevented in those portions of the extreme section which are most liable to rust.

An advantage resulting from the invention is, that the longitudinal irons make it possible to securely hold the platform at different heights on the chimney. The platform can be further used as scaffolding for the erection of the chimney so that, by means of a pole, adapted to be connected to the chimney and having an oscillatable jib, the different sections can be built up by a few workmen.

An embodiment of the invention is illustrated, by way of example, in the accompanying drawing, in which:

Fig. 1 is a side-elevation, showing the top-part of an iron-plate chimney with a platform secured in position.

Fig. 2 shows on larger scale a cross-section of a section.

Fig. 3 is a partial longitudinal section showing the joints of two sections.

Fig. 4 is a corresponding side-elevation.

Fig. 5 is a longitudinal section showing the top-portion of a chimney with the protecting ring.

Fig. 6 shows in longitudinal section and on larger scale the flange-connections of the sections according to Fig. 1.

Fig. 7 is a cross-section on line VII—VII of Fig. 1, shown on a larger scale.

Fig. 8 is a cross-section on line VIII—VIII of Fig. 1.

Fig. 9 is a longitudinal section showing a portion of Fig. 1 on larger scale and especially a modified form of construction of the means for securing the platform in its position.

Fig. 10 is a side-elevation of Fig. 9.

Fig. 11 is a horizontal section on line XI—XI of Fig. 9.

As shown in Fig. 1 the iron-plate chimney is built from a convenient number of similar sections 1, rigidly connected the one with the other in a suitable manner. Each section 1 is composed of two or more elements consisting of curved iron-plates so that the elements together form a cylinder. Each section has at each end a flange 5, consisting of an angle-iron fixed by rivets and having holes 3 spaced at suitable distances and designed to receive the connecting bolts 6.

As shown in Fig. 2 each section is composed of three elements 2 the vertical edges of which join directly so that joints 7 are formed. These joints 7 are covered by longitudinal irons 8, preferably of T-shaped cross-section. The longitudinal edges of each section-element are fixed on the transverse arms of the T-iron by means of rivets. In this manner the resisting capability of each section is increased so that the chimney is secured against bending moments due to wind-pressure.

As shown in Fig. 1 each section may be composed of four elements or of any other number of elements. Instead of T-irons two angle-irons may be used for connecting the section-elements, each section-element being connected by rivets to the arm of the corresponding angle-iron. To complete the section, the free arms of the angle-irons are then connected the one with the other by rivets to form longitudinal irons.

The longitudinal irons 8 have on the inner sides of their front-ends cut out portions 9, designed to accommodate the angular flanges 5 at the ends of the sections (Figs. 3 and 4). These angular flanges have in their edge-por-

tions cut out portions 10 through which the longitudinal irons 8 extend. For reinforcing the longitudinal irons the ends of two irons belonging to different sections are rigidly connected the one with the other by fish-plates 11 and screw-bolts 12. This fixation ensures at the same time that all prejudicial bending moments acting upon the chimney are transformed into axial tensile or compressive stresses.

In chimneys of this type the inconvenience makes itself felt which is due to the freely exposed upper flange, that destruction by rusting begins at the connecting joints of these flanges as shown in Fig. 5. The upper edge of the chimney is therefore covered by a ring 13 designed to protect it against rain. This ring 13, which is loosely mounted, consists of a flat ring, bearing on the upper edge of the chimney and of two extensions 14 and 15. The outer extension 14 is conical and designed to keep the rain-water away from the chimney and the inner cylindrical extension 15 is cylindrical and of such length that no rain-water can get at the inner surfaces of the upper portions of the iron-plates of the chimney.

On the chimney shown in Fig. 1, which is cylindrical, a platform 16 is mounted so that it can be raised and lowered. This platform 16 has a guard-rail 17. On the lower surface of the platform 16 double angular pieces 18 are fixed between which, on cross-bolts 19, are rotatably mounted. These guide-rollers 21 are rotatably mounted. These guide-rollers roll with their grooves 20 on the webs of the longitudinal irons 8 (Figs. 6 and 7) so that the hoisting and lowering of the platform can be carried out free of disturbances.

With regard to each longitudinal iron the platform is fitted with two parallel bearing pieces 22 being arranged in radial direction and formed for journalling a transverse axle 23 on which two bars 24 are loosely mounted. In the free ends of every two bars 24 a screw-bolt 25 is fixed by means of which these bars 24 can be fixed on the webs of the longitudinal bars 8 by inserting the screw-bolts 25 through corresponding holes 26 of said longitudinal bars. For each longitudinal bar of the chimney one bearing piece 22 with oscillatable bars 24 and screw-bolts 25 is provided. Any number of holes 26 may be provided in the longitudinal bars, according to the distance 55 between the different working positions in which the platform is designed to be held on the chimney.

Lugs 28 are arranged on the upper edge of the chimney or on arms 27 extending from said upper edge, said lugs being designed for suspending blocks and tackles or pulleys blocks 29 hooked at the other end into corresponding eyes 30 on the platform.

The movable platform presents the advantage that it may be used already at the build-

ing of the chimney, when it is constructed, as will be hereinafter described to hold a pole by means of which the sections, designed for building the chimney can be hoisted to be swung to above the section which has been fixed in position. The fresh section is then lowered on the fixed section. After the two sections have been connected the one with the other by means of screw bolts 6, the blocks and tackles are detached and suspended again in the lugs of the upper edge of the section which has been last put in position. After releasing the platform by removing the screw-bolts 25, the platform can be hoisted again to be secured in the fresh position so that another section can be put on.

When the chimney is finished, the platform remains in the upper position, secured on the longitudinal bars 8, as shown in Fig. 1. The blocks and tackles might be removed to be stored to prevent premature destruction by weather and wind.

When the chimney has to be freshly painted, it is not necessary to arrange a scaffold. A workman climbs up onto the platform, pulls up the blocks and tackles and hangs the same on the upper edge of the chimney, whereupon the platform may be lowered to the ground after the fixation-means have been removed, so that the painters and the material can be hoisted on the platform to the top of the chimney. The chimney is painted as usual from the top-end towards the bottom-end. After the painting the platform is hoisted to the top-end of the chimney and secured in this position.

At the building of iron-plate chimneys it has been found that the outer circumference of the chimney is not accurately cylindrical, and that the circumference of the chimney is not regular from the top to the bottom so that the guide-rollers of the loaded platform might not securely and uniformly bear against the longitudinal irons. The arrangements shown in Figs. 9 to 11 are designed to avoid this inconvenience. The platform 16 has on its lower side as many radial guide-bars 31 as there are longitudinal irons on the chimney, the central webs of said guide-bars bearing on guide-rollers 32, mounted in double brackets 33 guided by means of rollers 34 on the longitudinal irons 8 of the chimney. The brackets 33 are preferably double so that the rollers 32 and 34 can be mounted between the two brackets on pivot-bolts 35.

On a stud 36, projecting one from the outer side of each bracket 33, link-arms 37 are pivotally mounted which extend through radial slots 38 of the platform 10. When the platform is being hoisted, these link-arms 37 rest loosely on the outer edge of the platform. For securing the platform in its position the free end of the arms 37 are fixed to the cor-

responding longitudinal irons 8 by means of screw-bolts 25 engaging with the holes 26 of said longitudinal irons.

The hoisting and lowering of the platform is effected, as mentioned above, by means of blocks and tackles 29. A platform with the arrangements shown in Figs. 9 to 11 will be pulled downwards in its secured position by the weight of the brackets, wherefrom results an inwardly directed weight-component, by the action of which the rollers 34 of the brackets are constantly pressed tightly against the longitudinal-irons 8 so that any undesired turning of the platform is excluded and the work can be carried out securely, even when a strong wind is blowing and when the outer diameter of the chimney is irregular.

I claim:—

1. An iron-plate chimney composed of several sections forming together a cylinder, comprising in combination with the sections consisting each of several elements, longitudinal T-irons fixed by rivets in the joints of said section-elements, a platform surrounding said chimney, means for guiding said platform on said longitudinal T-irons, and means for securely fixing said platform on said chimney at any desired height.

2. An iron-plate chimney composed of several sections forming together a cylinder, comprising in combination with the sections consisting each of several elements, longitudinal T-irons consisting of profiled irons having holes in their web fixed by rivets in the joints of said section-elements so that they project radially over the outer surface of said sections, a platform surrounding said chimney, means for guiding said platform on said longitudinal T-irons, and means for securely fixing said platform on said chimney at any desired height.

3. An iron-plate chimney composed of several sections forming together a cylinder, comprising in combination with the sections consisting each of several elements, longitudinal T-irons fixed by rivets in the joints of said section-elements, a platform surrounding said chimney, means for guiding said platform on said longitudinal T-irons, means for securely fixing said platform on said chimney at any desired height consisting of brackets fixed on the lower side of said platform, pairs of link-arms rigidly connected to the lower side of said platform, a pair of guide rollers in each pair of arms adapted to run on said T-irons, and a pair of links connected to each pair of brackets adapted to be connected to said T-irons for securing said platform on said chimney at any desired height.

4. An iron-plate chimney composed of several sections having flanges, screws connecting the flanges of the several sections, longitudinal T-irons fixed on said sections connected with each other and covering the longi-

tudinal joint of said sections, a platform surrounding said chimney and having radial slots, pairs of brackets fixed on the lower side of said platform, rollers in the lower end of each of said brackets running on said T-irons, rollers mounted freely rotatable near the upper edge of each bracket in the horizontal plane and designed to guide said platform, radial bars on the lower side of said platform resting upon said pairs of rollers, pairs of links hingedly mounted on said brackets and upwardly projecting through said radial slots of said platform adapted to connect said brackets to said T-irons and for automatically adjusting said platform in radial direction.

5. In an iron plate chimney composed of several sections forming together a cylinder, in combination with said cylinder composed of sections consisting each of several elements, longitudinal T-irons fixed on the joints of said section-elements having holes at suitable points, a platform surrounding said chimney and having radial slots and an aperture for a winch-rope, brackets connected to the lower surface of said platform, link-arms pivotally connected to said brackets and extending through said radial slots in said platform, and means for fixing the ends of said link-arms in said holes of said T-irons.

In testimony whereof I affix my signature.
EUGEN HABER.
